SUGAR DISPENSER

Don De Fano, River Grove, and Robert I. Kallman,
Geneva, Ill., assignors to Bloomfield Industries, Inc.,
Chicago, Ill., a corporation of Illinois

Filed Dec. 18, 1958, Ser. No. 53,818

Term of patent 14 years

(Cl. D44—22)

Fig. 1 is a front elevational view of a sugar dispenser, showing our new design;

Fig. 2 is a side elevational view;

Fig. 3 is a top plan view; and

Fig. 4 is a perspective view thereof.

We claim:

The ornamental design for a sugar dispenser, substantially as shown!
